The diagram illustrates a speaker system with two channels. A central vertical line represents the axis of symmetry. At the top, a speaker icon is labeled '10'. Above the central line, the text '8 ch' is written. Below the central line, the text '9 ch' is written. Two rectangular boxes, labeled 'r' and 'r'', are positioned on either side of the central axis. Each box contains a speaker icon and a wavy line representing sound. The box labeled 'r' is associated with the top channel (8 ch), and the box labeled 'r'' is associated with the bottom channel (9 ch). The number '2' is located at the bottom center. To the right of the diagram, the text 'Fig. 6.' is written.

EDWARD F. COLLADAY, OF WASHINGTON, DISTRICT OF COLUMBIA

WIRED BROADCAST DISTRIBUTION

Application filed May 18, 1926. Serial No. 110,012.

My invention relates to broadcast distribution over line wires to subscribers' stations. It has for its object the improvement of such distribution in divers particulars as hereinafter appears. Stated generally, the invention contemplates the use of multiplex amplifying and transmitting means at the central distributing office, which will send out current of identical frequency but 5 placed in phase over different conductors, which may be wires or any equivalent media; and the provision at a receiving station of an instrument which will respond to the current in displaced phases, while 10 affected by ordinary currents transmitted over the circuits.

My invention is illustrated in the accompanying drawings, in which

Fig. 1 is a diagram showing a duplex arrangement of tubes at a central office for amplifying and transmitting currents over wire circuits to a substation.

Figs. 2, 3, 4, 5, 6, 7, and 8 are respectively diagrams of modifications in the receiving 25 apparatus.

Referring to the drawings, 1 and 2 represent a pair of metallic circuit line wires extending from a central station C to a subscriber's station S and for the sake of completeness being assumed to represent a telephone line having terminal apparatus J at the central office and a subscriber's telephone T at the substation. Bridged across the line at the central station are two vacuum 30 tubes V—V', having their plate circuits p—p' connected to the line wires 1—2 respectively. The grid circuits are connected by a common coupler to the circuit 3 terminating in the switch m by which it may be connected either to a local metallic circuit 35 or to a relay circuit 33. The relay N is supposed to receive broadcast matter, either by radiation, or by carrier current, or by other means, and to demodulate or otherwise 40 reduce the same to audio frequencies which are impressed on the circuit 3. If it be desired to receive and transmit through tubes V—V' carrier current or superaudio frequencies modulated this will necessitate the 45 addition of a detector or detectors at the

subscriber's station as shown in Fig. 8. These tubes are connected with their grids to the opposite sides of line, and their plate circuits connected in parallel to the primary of the induction coil r², the secondary r³ of which is connected to the usual receiver or 55 loud speaker either directly or through an amplifier of any suitable type. This same arrangement of receiving tubes V² V³ may be employed for receiving audio frequency 60 waves over the line, in which case the tubes will act as amplifiers, without other change from the showing of Fig. 8.

In both Figs. 1 and 8 the usual "A" and "B" batteries are provided for the filament 65 and plate circuits of the tubes V—V'—V² V³.

At the subscriber's station as shown in Fig. 1 an electromagnetic receiver R is shown provided with a pair of choke coils ch and a pair 70 of electromagnetic operating coils r—r' supposed to produce polar changes in a suitable magnetic circuit acting upon the diaphragm or other sound producing agency d. The choke coils may be wound to supplement each 75 other for the metallic circuit, and to balance or neutralize each other in effect for the simplex circuit composed of the two wires 1—2 and the ground 4. The receiver coils r—r' are wound to very high resistance, 80 which is rendered possible first by the high resistance of the plate circuits of the tubes V—V', and second by the voltage of the B battery which would have in such an amplifier a voltage of the order of 90 or 100, or 85 more. As the current in such a circuit is very small, the present arrangement gives a number 90 of advantages: first, the resistance of the line wires is halved; second, the current rises in one wire as it falls in the other, hence the inductive effect on other wires or pairs in a cable is negligible; third, the effect of the undulations in opposite phase in the two plate circuits is cumulative in the receiver R assuming the coils r—r' to be properly 95 wound to supplement each other in effect on the diaphragm. The imposition of the tubes V—V' and the receiver R on the line has no effect upon the telephone use of the line, because of the very high ohmic resistance in- 100

volved as well as the choking effect of the coils ch ; and finally the telephone currents in the metallic circuit will have no effect upon the receiver R , and while the telephone T is in a bridge of the simplex circuit, the adjustment of the electromagnetic constants in the circuit may be made such as to prevent any substantial leakage of the broadcast current through the telephone receiver, even though the latter be off the hook during broadcast receiving. A slight leakage of this is not detrimental, because it serves to remind telephone users that radio receiving is going on; and it can be prevented entirely by properly relating the telephone bridge to the bridge of the receiver R , which is contemplated by but forms no specific part of the present invention.

Fig. 2 shows the coils $ch-ch$ wound on a ring core in proper direction to neutralize each other for the simplex circuit and supplement each other for the metallic circuit, to prevent short circuiting of the telephone.

Fig. 3 shows another method of winding the coil ch on separate cores, the receiver in this case being a loud speaker connected to the simplex circuit through a transformer tr . The primary windings of this transformer $r-r'$ function the same as in the receiver R in Fig. 1, but should be so related to the secondary windings that the undulations in the secondary circuit are cumulative.

Fig. 4 shows an arrangement similar to Fig. 3 but with the coils $r-r'$ acting directly on the diaphragm d .

Fig. 5 shows a modification in which the coils $ch-ch'$ are wound upon a common core. These windings are supposed to be of low ohmic resistance but in series producing high inductance and in parallel neutralizing each other for any electromagnetic effect, while coils $r-r'$ have a very high resistance of the order of several thousand ohms each.

Fig. 6 shows another modification wound on a closed core, in which each of the windings ch is doubled on itself, being preferably formed of two wires wound together on the core and then connected as shown. The joint ends 5-6 are connected by a wire 7, the ends 8-9 are connected to the line wires 1-2 respectively, and the ends 10-11 go to the coils $r-r'$ or their equivalent. This same circuit is schematically shown in Fig. 7, with the cores indicated as separate. Currents in the simplex circuit pass from the two line wires to ground through the double windings ch in series, so that each double winding neutralizes itself so far as any effect on the core is concerned, but the effect of the currents passing in the coils $r-r'$ is maximum. Currents from the metallic circuit on the other hand would pass from wire 8 through one-half of the winding of the first coil ch to the point 5, then through the wire 7 to the point 6 and through one-half of the second

winding ch' to wire 9. This affords a maximum of impedance between the wires 8-9, with only ohmic resistance of the coils which is low in the grounded circuits.

It is to be understood that numerous changes and modifications may be made in the circuits thus described without departing from the principles of this invention which is presented herein as one embodiment only of principles which are applicable to many forms of circuits and apparatus. It is possible with this arrangement to convey enough energy over the two conductors of the metallic circuit to operate a loud speaker at the subscriber's station without any local amplification. It is also possible to operate the simplex circuit as shown, without any inductive effect on any other circuit in the same cable. Various other benefits will occur to those skilled in the art as well as the possibility of modifications referred to, which are intended to be included herein insofar as they fall within the scope of the appended claims.

What I claim is:

1. A transmitting station, a receiving station, a two-wire metallic circuit extending between them, means for producing a current flow in said metallic circuit as such, means at the transmitting station for producing current impulses in the two wires of the metallic circuit in parallel, as a phantom circuit, with phases displaced, together with a receiver at the receiving station and means to recompose the displaced phases and cause the same to supplement each other and to act cumulatively upon said receiver, said transmitting station being a service station, said receiving station being a subscriber's station, the flow of current in the metallic circuit being in response to regular service requirements, and the flow of current in the phantom circuit being in response to special service requirements, the regular service instruments being irresponsible to the special service current, and the special service instruments being irresponsible to the regular service current.

2. A system comprising a plurality of metallic circuits, as described in claim 1, each with independent means to transmit and receive signals over the metallic circuit, and each having an individual phantom connection to propagate desired undulations in the two sides of the metallic circuit in parallel, with means to displace the phases thereof, whereby disturbing inductive effects on other circuits are avoided.

3. A system as described in claim 1, in which the transmitting station is a centralized service station, with a plurality of receiving stations and a plurality of metallic circuits extending from the service station thereto individually, a duplex vacuum tube relay for each circuit at the service station, means for transmitting signals over the me-

tallic circuit and means to receive the same, means to supply special signals to said vacuum tube relays and to cause the same to impress undulations corresponding thereto

5 on the two sides of a metallic circuit in parallel and with their phases displaced, together with means at each subscriber's station adapted to receive and recompose said dephased undulations, and a receiver responsive thereto.

10 4. A combined service system, a special signaling system comprising a centralized service station, subscribers' stations, and individual metallic circuits interconnecting said

15 subscribers' stations and said service station, means for signaling to and from a subscriber's station over his metallic circuit, means at the service station for producing signaling currents of special service character,

20 a duplex relay for each metallic circuit, having its input terminals connected to receive said special service signals, and having its output terminals connected to the two sides of the metallic circuit, a receiver at each

25 subscriber's station and means to receive and properly relate the special service signaling currents to produce cumulative effects upon said receiver, said last named means and said receiver being irresponsive to the regular

30 service currents in the metallic circuit.

In testimony whereof I hereunto affix my signature.

EDWARD E. CLEMENT.
